UNITED STATES PATENT OFFICE.

RAYMOND D. SMITH, OF SCARSDALE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

QUICK-MAKE AND QUICK-BREAK ELECTRIC SWITCH.

Application filed February 25, 1921. Serial No. 447,662.

A principal object of this invention is to provide a novel form of switch mechanism for causing a snap action both in the closing and opening movements of two electric contacts and which shall be particularly suited for a type of switch mechanism wherein an automatically retractable detent is employed for controlling the circuit-breaking movement of the contacts. 10 An example of this type of switch mechanism is fully illustrated and described in my co-pending application, Serial No. 428,100, filed December 3, 1920 wherein a thermostatically-positioned detent automatically operates to prevent circuit-breaking action of the switch a pre-determined interval of time after usual actuation of the control agency to extinguish the light, and then causes a quick break of the circuit. It will 20 be seen from reference to my co-pending application mentioned above, that the closing of the contacts to make the circuit there constitutes a relatively slow movement effected through direct actuation by the control agency. It is a specific object of this improvement to eliminate the possibility of producing a slow or hesitating closing of the contacts and preferably through simple modification of one of the contact members 30 not disturbing the originally designed co-action of said contact and the thermostatically positioned detent in their circuit controlling movement.

A further accomplishment of the present improvement is the provision of a rugged and practicable means for adjusting the amount of engagement between the above mentioned contact and detent so as to vary the time interval consumed in thermostatically caused retraction of said detent to permit escapement of said contact.

For the accomplishments of the above and other objects, my invention consists in the novel provisions and constructions illustrated as preferred embodiments of the invention in the accompanying drawings and hereinafter described.

In the drawings, Fig. 1 is an outline view in elevation showing a certain form of electric lamp pull socket with casing cut away to disclose the interior switch mechanism, which is similar to that in my co-pending

application hereinbefore referred to, and to which the present improvement in electric switch mechanism is especially suited, but not limited. Fig. 2 is an inverted plan view of the same switch mechanism looking upwardly from the plane 2-2 in Fig. 1;—the insulating base being removed. Fig. 3, on an enlarged scale, shows elements corresponding to certain parts in Fig. 2 with the movable switch contact provided with my new quick-make mechanism; the parts appearing as in the full "off" position of the switch. Fig. 4 is a fragmentary side view looking at the right of Fig. 3. Fig. 5 shows the same parts nearly at the end of their circuit-making movement. Fig. 6 shows a dotted and full line position of the same parts, the dotted lines representing the full "on" position of the switch, and the full lines representing the position of parts prior to the automatic, circuit-breaking action. Fig. 7 shows on a reduced scale the same parts as in Figs. 3, 5 and 6 positioned as per the dotted lines in Fig. 8 with a diagram of their electrical connection. Fig. 8 is a similar diagram of connections, with parts positioned as per full lines in Fig. 6. Fig. 9 shows a modification of the stationary contact with provision for adjusting the engagement between the movable contact and its controlling detent. Fig. 10 shows another means for adjusting this engagement, and also a different form of spring for effecting the quick "make" movement. Fig. 11 shows still another modification wherein details of construction are further varied. Fig. 12 shows a cross section on the plane 12-12 in Fig. 11. Fig. 13 shows a simple provision applicable to the former design of switch actuator whereby at proper times the thermostat may be properly reinforced to insure correct relative action of the contacts and detent. Fig. 14 is a fragmentary sectional view taken on the plane 14-14 in Fig. 13.

Throughout the figures of the drawings different views of the same element are designated by the same reference character.

In Fig. 1 the main socket structure, which is illustrative of any useful application of a switch mechanism embodying my present invention, consists of the usual upper insu-

lating cap 10 and insulating base 9, above the former of which are carried the screw shell 11 the insulating spacer block 12 and center contact 13; and below the latter of which, depends the threaded lamp receptacle 14 and central contact tongue 15; this type of socket switch structure being of the nature of an attachment adapted to insert between the common form of lamp socket 10 and an ordinary electric lamp bulb (neither of which are shown).

As may be more fully understood from reference to my co-pending application hereinbefore mentioned, the switch actuating agency includes the two pull chains 16 and 17 which pass through the bell mouth 18 for oscillating a segment structure 19 to which is rigidly fixed the contact controlling cam 20 which latter, together with segment 19, is pivotally mounted to oscillate one quarter turn in a horizontal plane about the pivot screw 21 and which is held in place on its pivotal mounting by a double armed spring washer 22 mounted on the terminus 23 of main bracket member 24.

The swinging of cam 20 causes the spring-leaf contact 26 to flex to and from a position for contacting with stationary contact 27, contact 26 being automatically caught and held in contact with stationary contact 27 by interception of the free end of thermostat 28, which latter when energized by a resistance wire 29 wound thereon in insulating relation, moves the free end of said thermostat out of a position intercepting the free end of contact 26. Thermostat 28 is composed of a laminated strip encircling the switch mechanism and securely riveted at one end to bracket 24.

40 In predetermined relation to the swinging movements of cam 20, an auxiliary contact member 31 makes and breaks circuit in properly timed relation therewith for which purpose, contact 31 is faced with insulation 45 32 secured thereto by the conductive eyelet 33 for purposes of circuit control as later to be explained.

In Figs. 3, 4 and 5 the contact 26 is shown in modified form as 26' in accordance with 50 the principles of my present improvement. The formerly integral end of contact 26 is replaced by a movable contact shoe 34 fixed at the end of a stem 35 which latter is slideable lengthwise in bearings 36-36 carried 55 by the leaf-spring 26'. A coiled spring 37 surrounds the stem 35 pressing between lower bearing 36 and a pin 38, which latter limits the upward movement of stem 35, and causes 60 spring 37 to press contact shoe 34 against the end of thermostat 28. When cam 20 is swung clockwise in Figure 5, the contact shoe 34, riding in contact with thermostat 28, is depressed by the latter against the light tension in spring 37 sufficiently to prevent contact- 65 ing of shoe 34 with contact 27 until said

shoe escapes the end of the thermostat 28, at which time it snaps to the position shown in Figure 6, thus producing the desirable quick "make" action in the contacting of members 34 and 27.

70 In former types of this switch mechanism, contact between members 26 and 27 can be broken only under control of the thermostat 28 as, for instance, when the latter, through thermal energization by the resistance wire 29, is caused to flex to its dotted-line position in Fig. 6 thus permitting shoe 34 to be snapped away from contact with member 27 by the resiliency in carrying member 26'. It will be seen that the present improvement 80 makes it impossible through any manipulation of the pull chains 16 and 17 to cause other than a quick-break and also a quick-make of the circuit.

85 The operation of the switch as a whole with my present improvements embodied therein will be clear from reference to Figs. 7 and 8. In Fig. 7, the parts have been moved to the full "on" position so that current will be continuously supplied to the lamp through the following conductors: 11-27-34-35-26'-20-33-31-14 to the lamp indicated by "L" thence through 15, 13 and back to the line. In Fig. 8, cam 20 has been retracted leaving contact 34 tensioned for escapement from thermostat 28. The current here is through the following conductors (contact between cam 20 and eyelet 33 having been broken): 11-27-34-35-26'-24-28-29-14 to the lamp "L" 100 hence back to the line through 15 and 13 as before. It is thus seen that in Fig. 8, resistance wire 29 is thrown in series with the lamp which thermally energizes the thermostat 28 which releases contact 34 and breaks the circuit after a brief interval of delay. One use for this principle of switch action is to prevent being left in darkness when turning out the light, the delay interval being sufficient to permit a comfortable exit before 110 the light goes out.

105 It is noted that in the old form of slow-make switch mechanism illustrated in Fig. 2, the stationary contact 27 is formed as a thin leaf-spring for permitting its necessary 115 yielding to accommodate clearance movement of contact 26 when the latter is pushed out into latching engagement with thermostat 28 for making the circuit. It is also to be noted from the curvature and relation of 120 contact 26 and thermostat 28 that the latter, in this arrangement, is the member which yields to perform the latching action. The present improvement, however, contemplates the employment of so light a spring (such as 37 in Figs. 3, 4 and 5) acting on the contact 34 that the pressure of this spring against the end of thermostat 28 is not sufficient to cause an appreciable deflection of the latter, but effects the latching engage- 130

ment of contact shoe 34 with the thermostat, through yielding (mainly or solely) of the contact shoe 34.

In Fig. 9, a modification is shown wherein stationary contact 27 (which is not here required to be yielding for the reasons explained above) is formed as a rigid member 27' carrying at its contact making end an adjustable contact-making screw 39 which 10 by a change of its setting (as mounted in member 27' and secured by the lock nut 30) operates to determine the amount of engagement between contact shoe 34 and the end of thermostat, while permitting all of 15 the other designed functions of the contact parts to take place as hereinbefore described.

Fig. 10 shows a modification, in which a leaf-spring 44 replaces coil spring 37 and wherein means for adjusting the engagement 20 between contact shoe 34 and thermostat 28 are provided in the form of a set nut 45 and lock nut 46 carried on stem 35,—this form of spring being preferable for maintaining 25 good electrical contact between stem 35 and the spring-leaf carrying member 26' in cases where electrical conductance from one to another of these parts is required.

Fig. 11 shows a still further simplification embodying the principles of this invention, 30 wherein the stem 35 is replaced by a strip member 47 guided in bearings formed by turning over tongues 48, 48 carried on spring-leaf carrying member 26'', said member 47 in this case having substantially the 35 same form at its contact-making end as the old form of spring-leaf contact 26 in Fig. 2 and being pressed upwardly toward the thermostat 28 by a thin leaf-spring member 49, secured in this case by the same holding 40 means or rivet 51 that secures member 26''. A stop 52 can be provided to limit upward movement of member 47.

Figs 13 and 14 show a re-enforcing provision for the thermostat in the form of an upward projection 41 secured to the inner face of the curved thermostat 28 for engaging with a cam-like, curved strip 42 carried on the operating segment 19, which acts to re-enforce the free end of the thermostat 50 28 against outward thrust of spring 37, except when it is desired that this flexure should take place to cause automatic circuit breaking action. Thus, in Fig. 13, where the cam and operating segment 19 (which 55 move in fixed relation) both occupy their position corresponding to full "off" position of the switch, it is clear that as soon as cam strip 42 starts to swing counter-clockwise with the operating segment 19 and cam 20, it 60 will engage thermostat projection 41 (even though the latter be already somewhat outwardly displaced by the thrust of spring 37) and will force the latter into its normally innermost position where it will be retained by 65 continuation of the engagement of cam strip

42 with projection 41 and until cam shoe 34 has escaped the end of thermostat 28 which relieves the latter from the thrust of spring 37.

It will be obvious that within the scope 70 of my invention many such departures may be made in the details of construction additional to the various modifications herein illustrated and described.

The following claims will therefore be understood in no way to limit the subject matter of invention to the precise disclosures of the foregoing specification but shall be interpreted as covering all equivalent arrangements and constructions that may fairly be 80 included within the spirit of the invention defined.

What I claim is:

1. A quick-make and quick-break mechanism for thermostatically controlled switches 85 embodying, in combination; a relatively stationary contact member; a relatively movable contact member; means tending to separate said two members; a thermostatically controlled latch movable to and from a position preventing the separation of said two members, and means acting on said movable member co-operatively with said latch member to cause a quick snap action thereof 90 when the latter approaches said stationary member.

2. A quick make-and-break switch mechanism embodying, in combination; a stationary contact; a movable contact, spring-im- 100 pelled in relatively transverse directions re- spectively to make and to break the circuit; and a contact-controlling detent; the movements of said movable contact in each of its said directions being controlled by escape- 105 ment thereof from said detent.

3. In a thermostatically controlled, quick- make and quick-break switch mechanism in combination; a stationary contact; a movable contact mounted for movement in relatively transverse directions respectively to 110 make and to break circuit with said stationary contact; and a thermostatically positioned detent; the movements of said movable contact being controlled in both circuit-breaking and circuit-making direction by 115 said detent.

4. A quick-make and quick-break switch mechanism embodying in combination a relatively stationary contact, a movable contact member co-operating therewith and 120 spring-urged in transverse paths respectively to make and to break the circuit; and a retractable detent to control separation of said contacts,—said detent being further 125 normally stationed to depress the movable member to a tensioned opposed position for producing a quick circuit-making action of the latter.

5. In an electric switch, the combination 130 of a contact movable in one direction to

- make the circuit and movable in a relatively transverse path to break the circuit, and a detent arranged to restrain said contact at different times from each of its said movements while simultaneously permitting its other movement.
6. In an electric switch embodying two contact members and a thermostatic latch to control the separation thereof; means carried by one of said contacts and co-operating with said thermostatic latch to produce a snap movement of the last mentioned contact near the end of its movement toward the other contact.
15. 7. In an electric switch embodying an operating agency and two relatively movable contacts adapted to be closed by one movement of said agency and separated by a subsequent movement thereof; in combination; means automatically operative to delay the separating movement of said contacts responsive to control movement of the operating agency; and means automatically operative to produce a snap action of one of said contacts to close the circuit responsive to a subsequent actuation of the said control agency.
8. Automatic switch mechanism embodying in combination a stationary contact; a movable contact made of two parts, the first part being mounted for spring-caused movement away from said stationary contact and the second part being mounted on said first part and spring-impelled in a direction to make contact with said stationary contact; spring energizing means; and a restraining detent for causing the quick separation of said second part of the movable contact from said stationary contact; and separate spring-energizing means and detent mechanism for causing the quick circuit-closing movement of said second part of the movable contact member relative to said stationary contact.
45. 9. In an electric switch a stationary contact; a spring-leaf carrying-member; and a relatively movable contact carried thereby; said member being mounted to flex against its spring tension in a direction to bring said movable contact adjacent said stationary contact; a separate spring urging said relatively movable contact to a position for engagement with said stationary contact; and a common detent co-operatively arranged with said movable contact to cause both a quick separation of the latter from said stationary contact under the impulse of said spring-leaf holding-member, and also to cause a snap-closing movement of said movable contact with said stationary contact under the impulse of said separate spring.
10. In an automatic contact-breaking switch, a quick-action contact-breaking mechanism embodying in combination; a thermostatically positioned detent and a tensionable switch contact arranged to be locked thereby in circuit making position, said detent being relatively unyielding and said contact having tension means yieldingly to press it against said detent for causing a snap escapement therefrom into circuit-making position.
11. In an automatic contact-breaking switch a quick contact-breaking mechanism embodying in combination; a thermostatically positioned detent; a contact shoe mounted for travel in spring pressed contact with said detent, and adapted to escape said detent for quick snap movement into its circuit making position.
12. In an electric switch, the combination of a contact controlling detent; a switch contact movable under spring impulse in two respectively transverse paths relative to said detent; the escapement of said contact from said detent in one of said paths causing a quick break of the circuit, and the escapement of said contact from said detent in the other of said paths producing a quick make of the circuit.
13. A quick-make and quick-break switch mechanism; embodying, in combination; a movable contact; spring mechanism connected thereto to actuate the same in two different directions; a control agent for moving said contact under the tension of said switch mechanism; and a detent operating to restrain said contact against spring caused movement in both of said different directions thereby to cause a snap action of said contact respectively to break and to make the circuit.
14. In an electric switch embodying circuit governing contacts normally tensioned to separate; an actuating member adapted to close said contacts; a thermostatic latch arranged to effect the automatic opening of said contacts when said actuating member is withdrawn; and mechanism acting on one of said contacts to produce a snap action thereof while said two contacts are being closed by said member.
15. In an electric switch, a pair of contact members, switching mechanism tending by successive movements to move one of said contact members with a snap action both into circuit-making and circuit-breaking positions respectively, a slow acting control device interposing a detent to intercept the circuit-breaking movement of said member thereby to delay for a substantial interval of time the movement of said contact member to its circuit-breaking position, and an adjustable device co-operating with one of said contact members to vary the extent of detent surface that must be traversed by said contact member to effect escapement of the latter, thereby to vary the time.
16. In an electric switch, contact members, a rotatable switching member tending by

successive movements to move one of the contact members relatively into circuit-making and circuit-breaking positions, a slow acting control device interposing a detent to the circuit-breaking movement to delay for a substantial interval of time the movement of said contact member to a circuit-breaking position, and an adjustable part acting on said contact member for varying the amount of engaging surface between the detent and said contact member.

17. In an electric switch, a contact member, a rotatable switching member tending by successive movements to move the contact member into circuit-making and circuit-breaking positions, and a slow acting control device to delay for a substantial interval of time the movement of said contact member to a circuit-breaking position, said switch including an adjustable part acting on said contact member for varying the time interval.

18. An electric switch having an operating agency and two relatively movable contacts one of which is adapted to be moved by successive movements of said operating agency respectively into circuit-making and circuit-breaking positions, means automatically operative to delay the circuit-breaking movement of said contact responsive to the control movement of the operating agency, and means automatically operative when

said controlling agency is subsequently moved to cause quick circuit-making movement of said contact.

19. An electric switch having a movable contact, a switch controlling member arranged positively to impel said contact toward circuit-closing position, a thermostatic detent adapted automatically to release said contact and permit its movement to circuit-breaking position, and means automatically to cause said contact to snap into its closed circuit position while being positively impelled toward said position by said switch controlling member.

20. In an electric switch, the combination with a contact, of a switch controlling member adapted through successive movements to initiate respective circuit-breaking and circuit-making movements of said contact, a thermostatic detent acting automatically to delay the completion of one of said movements until after the lapse of a time interval, and means automatically to complete the other movement with a quick snap action while said contact is being impelled by said member.

Signed at Boston, in the county of Suffolk and Commonwealth of Massachusetts, this 17th day of February, 1921.

RAYMOND D. SMITH.
